UNITED STATES PATENT OFFICE.

WILLIAM D. MCNAULL, OF RONCEVERTE, WEST VIRGINIA.

RADIAL-DRILLING MACHINE.

SPECIFICATION forming part of Letters Patent No. 472,546, dated April 12, 1892.

Application filed June 27, 1891. Serial No. 397,734. (No model.)

To all whom it may concern:-

Be it known that I, WILLIAM D. MCNAULL, residing at Ronceverte, in the county of Greenbrier and State of West Virginia, have invented certain new and useful Improvements in Radial-Drilling Machines, of which the following is a specification, reference being had therein to the accompanying drawings.

This invention relates to drilling-machines. The object of the invention is to produce a drilling-machine in which the drill may be adjusted to bore at an incline and may be advanced with its support from the main standard and be quickly adjusted and firmly held in working position.

Figure 1 is a broken vertical section of so much of a drilling-machine as is necessary to illustrate my invention. Fig. 2 is a broken elevation and partial section of the upper part of the frame or standard and the drill-head. Fig. 3 is an enlarged front elevation of the face-plate or bracket.

The numeral 1 denotes the base of a drilling-machine or, as commonly called, "metal-boring drill."

2 denotes an upright standard which supports a bracket or arm 3, on which the bed or boring-table 4 is supported. The bracket and bed are preferably vertically adjustable on the standard by any suitable means, as by rack 5 and pinion 6. The arm 7 passes through a mortise 17 in the standard 2, so as to have its face-plate 8 above the bed 4, and the plate 8 is preferably a disk, which may have curved slots 9 therein.

The drill-head 10 has a plate 11, which fits against the plate 8 and is preferably countersunk to receive said plate. The plate 11 may be turned on the plate 8 and secured in any adjusted position by bolts passing through holes in said plate 11 and through the slot 9 in plate 8, the bolts having nuts 13.

The edge of the plate 11 is preferably graduated, so that the head may be readily adjusted to any angle and the angle indicated. It is manifest that the position of the slots and bolts is not important, and any other suitable clamping mechanism by which the drill-head plate may be held when adjusted on the bracket will answer the purpose of the slots and bolts and nuts; also that it is immaterial which of the plates 8 and 11 embraces the

other. By inclosing a disk face-plate on one member in a recess in the other member, however, the strains are taken off from the fastening devices, as it would not be if two face-plates were simply clamped together face to face, as is common.

An arm or guide 15 projects radially from the swivel-plate 11 and may be integral therewith or firmly secured thereto. The guide-arm 15 can thus be adjusted to various angles in a circular plane, the center of which is the center of plate 8.

The driving-shaft 20 extends lengthwise through the hollow arm 7. Shaft 20 may be driven by means of a bevel-gear 21, engaging a bevel-gear on a counter-shaft supported on standard 2, arm 7 being slotted to admit the engagement of such driving-gear, or the shaft 20 may be driven by other suitable driving means.

The arm 7 is adjustable through the mortise 17, as by means of rack 23 on the arm, and pinion 24, supported on the standard and engaging said rack on arm, or the arm may be adjusted with screw and hand wheel or crank.

The arm 7 is held from rotation in the mortise in the machine illustrated by the rack 23, fitting closely in a slot or recess at one side of the mortise 17.

Shaft 20 passes through the face-plates 8 and 11 and has a bearing 80, attached to the plate 8 and preferably extending through a hole in the plate 11. A bevel-gear 30 on the end of said shaft is in position to engage a gear 31 on the drill-shaft or boring-bar.

A bracket 25 extends from the lower end of arm 15 and is perforated to form a guide-way for the drill-rod sleeve 33. A bracket 27 extends from the upper end of plate 11 and forms a bearing from the hub 32 or bevel-gear 31 in line with the guide-bracket 25.

The drill-rod or boring-shaft 35 passes through the sleeve 33 and the driving-gear 31 and is splined or otherwise constructed in usual manner to be free to move lengthwise through the driving-gear, but to turn with the gear. Thus the rotation of shaft 20 causes the drill-shaft to rotate at whatever angle it may be held by the brackets 25 and 27.

The face-plate 11 and arm 15 form the drill-carrier, and also carry supporting-brackets

28 and 29, in which the counter-shaft 40 has its bearings, said shaft extending parallel with the drill-rod, or nearly so. The shaft 40 has driving-pulleys 41 attached thereto and 5 the drill-rod 35 or gear 31 carries a corresponding set of pulleys 36, which pulleys 36 rotate with the drill-rod. Thus by belting from pulley 36 to pulley 41 the counter-shaft 40 may be driven.

10 Shaft 40 has a bevel-gear 42, which engages a similar gear 43 on a transverse worm-shaft 44. Said shaft 44 is supported in suitable bearings near the lower end of bar 15. A worm 46 on shaft 44 engages a worm-gear 47 15 on shaft 48, which shaft extends in proximity to the sleeve 33. Shaft 48 carries a pinion 49, which engages a rack 50, fixed to one side of sleeve 33. By this train of gearing the sleeve 33 can be caused to raise or lower the 20 drill-rod 35 and feed the drill to its work or raise it from the same, the drill-rod being free to turn in the sleeve 33, but made to move lengthwise with said sleeve by a collar or similar engagement, as usual in machines of 25 this class.

The shaft 48 and pinion 49 can be thrown out of engagement by a clutch 51, so that the worm 46 will not drive pinion 49, and thus stop the feeding of the drill. By hand wheel 30 or lever 84 on the end of shaft 48 the drill-shaft may be moved independently of the worm-gear when said gear is out of engagement.

It is apparent that the location of the clutch 35 is not material. It can be at any convenient place to throw the train of feeding-gears into or out of operation.

The shaft 44 and worm 46 may be actuated by the hand-wheel 52 to feed the drill-sleeve 40 forward.

Numerous modifications in the construction will suggest themselves. The important feature of the invention is the radial adjustment of the drill-bar and its guiding and feeding 45 mechanism without interfering with the driving connection between the drill-rod and the main driving-shaft.

What I claim is—

1. In a drilling-machine, a vertical standard 50 having a transverse mortise and a driving-shaft carried by said standard, an extensible transverse non-rotatable bracket or arm passing through said mortise, a drill-carrier ra-

dially adjustable on said arm, and a driving-shaft carried by the extensible arm and having 55 gears engaging the driving-gear of the main standard and the driving-gear of the drill-spindle in all positions of the bracket or arm, all combined substantially as described.

2. In a drilling-machine, the combination 60 of the vertical standard having a transverse mortise near the top, a driving-shaft, the extensible non-rotatable hollow arm passing through the mortise and having a radially-adjustable drill-carrier at its outer end, the shaft 65 in said arm having gears engaging the drill-driving gears and a gear on the main shaft in all positions of the arm, and a rack on said arm engaging a pinion carried by the main standard, whereby the arm may be extended 70 or withdrawn and the driving-gear maintained in constant engagement, substantially as described.

3. The combination, with the standard having a transverse mortise and a driving-shaft, an 75 extensible non-rotatable arm passing through said mortise, a face-plate at the outer end of said arm, a drill-carrier radially adjustable on said face-plate, a driving-shaft extending through and adjustable with the extensible 80 arm, and gears on said shaft engaging gears on the main driving-shaft and on the drill-carrier, substantially as described.

4. The standard and extensible non-rotatable arm having a circular face-plate, the drill-carrier having a circular recess to receive said 85 face-plate, clamping mechanism to retain said drill-carrier in radial adjustment on the arm, and the driving shafts and gears carried by the arm and drill-carrier, all in combination 90 substantially as described.

5. The combination, with the upright standard having a transverse mortise, the extensible non-rotatable arm passing through said 95 mortise, the circular face-plate at the end of said arm, the drill-carrier having a recess which receives said face-plate, and clamping-bolts passing through the carrier and through slots in the face-plate, all substantially as described. 100

In testimony whereof I affix my signature in presence of two witnesses.

WILLIAM D. MCNAULL.
